UNITED STATES PATENT OFFICE.

WILLIAM W. ROBINSON, OF DES MOINES, IOWA, ASSIGNOR TO IDEAL MANUFACTURING COMPANY, OF DES MOINES, IOWA, A CORPORATION OF IOWA.

ACCOUNT-KEEPING DEVICE.

No. 885,957.

Specification of Letters Patent.

Patented April 28, 1908.

Application filed January 12, 1904. Serial No. 188,807.

To all whom it may concern:

Be it known that I, WILLIAM W. ROBINSON, a citizen of the United States, residing at Des Moines, in the county of Polk and State 5 of Iowa, have invented certain new and useful Improvements in Account-Keeping Devices, of which the following is a specification.

My invention relates to that class of 10 account-keeping devices in which a series of file-holders are supported in a cabinet, each file-holder being designed to receive account files.

My object is to provide each of the file-holders of an account keeping device of this 15 class with an indicator, normally in a position from which it must be moved in order to withdraw from or deposit a file within its holder, so that an operator using the file-holder cannot neglect to move its indicator, and so that it may, after a certain period of 20 use, be certainly determined by a glance at the indicator, which of the file-holders have been used during said period.

My invention consists in the combination 25 with the cabinet and file-holders of the indicators, as hereinafter more fully described, pointed out in my claims and illustrated in the accompanying drawings in which:

Figure 1 shows a detail perspective view 30 of a part of one of the individual account file holders showing an indicator in position thereon. Fig. 2 shows a detail perspective view of part of an individual account file holder that portion of the indicator which is 35 arranged on the inside of the file-holder. Fig. 3 shows a perspective view of an individual account file holder having a modified form of indicator to be operated by the move-

ment required for opening the file holder, the 40 dotted lines indicating the position of the cover when opened and the adjusted position of the indicator. Fig. 4 shows a perspective view of a cabinet provided with a number of 45 compartments and also showing a number of individual account file holders in said compartments, and illustrates a modified form of indicator attached to the cabinet itself and operated upon the removal of an account 50 file-holder. The compartments of the cabinet from which the file-holders have been removed have their indicators set to position for indicating the removal of the file-holders. Fig. 5 shows an enlarged vertical sectional 55 view of a number of partitions in the cabinet

with the indicators attached thereto, one partition being provided with a file-holder, the indicator for this compartment being closed and the other partition being provided with an indicator in an open position. Fig. 60 6 shows a detail sectional view of a portion of the file holder illustrated in Fig. 3 with the cover in an open position showing the spring attached to the cover and in position for forcing the indicator to indicating position. 65 Dotted lines show the cover in its closed position and the position of the spring when the cover is closed.

Referring to the accompanying drawing, the cabinet is seen to be composed of a 70 bottom 10, top 11, sides 12 and 13, and a vertical partition 14. Between the partition 14 and the sides 11, I have arranged a series 75 of horizontal partitions 15, the forward edges of which preferably project a slight distance beyond the upright partition and sides.

Each file-holder preferably comprises a bottom 16, and a rigid front 17 secured to the bottom. Said rigid front is preferably provided with a card 18 designed to receive the 80 name of the person with whom the account is to be kept. Hinged to the top of the front 17 is the cover 19 and between the parts 16 and 19 are the files indicated by the numeral 20. These file-holders are preferably of such 85 size and shape that when placed in the compartments of the cabinet, the front ends of the file-holders will stand flush with the front edges of the horizontal partition so that each file-holder may readily be grasped between a 90 person's thumb and fore-finger by grasping ends of the front of the file-holder which projects beyond the sides and vertical partition of the cabinet.

My preferred form of indicator is shown in 95 Figs. 1 and 2 and comprises a metal plate 21 secured to the face of the front 17 and provided with a number of loops 22. The indicator proper is made of a single piece of spring wire and comprises two parallel end 100 portions 23, the extreme ends of which are bent outward away from each other at 24. These end portions 23 are slidingly mounted in the loops 22 and one of the end portions 23 is bent inwardly at 25 and 25^a, said bent portions 105 designed to engage the staples 21 and be yieldingly held against them, to thereby retain the indicator at either its outer or inner limit. The central portion of the indicator is formed into a head 26 which ex- 110

tends a slight distance beyond the adjacent end of the file-holder. Said head projects forward beyond the front of the file-holder, and formed integral with the head 26, is the 5 indicator point 27 projecting across the face of the front 17. The outer movement of the indicator is limited by the ends 24 engaging the loop 22 and the inner movement is limited by the head 26 striking the end of the 10 front 17. When the indicator is at its outer limit of movement, the point 27 stands close to the adjacent edge of the card 18 and when the indicator is at its inner limit of movement, the said point 27 projects over the said card so that it may be readily seen. In use 15 with this position of the device and assuming that the indicator is at its outer limit of movement it will be in normal position and will indicate the non-use of the file holder. 20 When the operator grasps the file-holder as required to draw it from the cabinet, he engages the head of the indicator and pushes it inward during the movement required for removing the file holder from the cabinet. 25 When the indicator is placed in this position it remains there during the time the file holder is used and after the file-holder is returned to the cabinet, and visibly indicates that the particular file-holder has been used. It is 30 practically impossible to remove the file-holder from the cabinet without setting the indicator to its position indicating the use of the file.

In the modified form shown in Fig. 3 of the 35 drawings I have provided a spring 28 secured by the rivet 29 to the under surface of the cover 19 near the front end thereof. This spring projects forward beyond the front 17 and then downwardly across the face of the 40 front 17. This spring 28 is normally in position with its front end portion at about right angles to its body portion and the pivotal point of the hinged cover is a short distance under the cover. When the cover is moved 45 from its closed position to its open position, which latter is indicated by solid lines in Fig. 6, the spring 28 will straighten out and in doing this, it will push the indicator arm which it engages downwardly, thus throwing the 50 indicator point toward the center of the file holder and upwardly, as shown by dotted lines in Fig. 3. By having the pivotal point of the cover below the cover, the forward end of the spring 28 would be somewhat lower 55 when the cover is open than when the cover is closed and by having the spring so arranged that it will straighten out as the cover is opened, its lower end will be much lower when the cover is open than when closed. 60 The indicator point 30 is pivoted to the front 17 and is provided with a right-angled extension or arm 31 which arm stands directly beneath the end of the spring 28, when the cover is closed and the indicator in its non- 65 indicating position, and when the cover is

open, the indicator point is moved inwardly toward the center of the book and upwardly to position indicating the use of the file holder. I have provided means for supporting the indicator in either of said positions by forming on the front 17 a raised portion 32 in the path of the extension 31 so that said extension in moving from one position to the other passes over the raised portion, and it will be yieldingly held in either position on 75 account of said raised portion 32.

In the modified form shown in Fig. 4 and Fig. 5 of the drawings, the indicator point is secured to the cabinet instead of to the file-holder and each indicator comprises a plate 80 33 fixed to the under surface of the horizontal partition 15. This plate is made of spring metal and is provided with an oval loop 34 at its outer end, which loop projects slightly beyond the partitions 15. The indicator point 85 35 is provided with a flattened pin 36 admitted into the oval loop 34. When the indicator 35 is in a horizontal position, the flattened pin 36 fits in the oval loop 34 and thus holds the indicator in this position. When 90 pressure is applied to the indicator 35 in a downward direction then the sides of the oval loop 34 are sprung apart and the indicator 35 is lowered to the position shown at the bottom of Fig. 5.

In practical use and assuming that a cabinet be provided with a series of file-holders, one for each party with whom an account is kept, and assuming further that the keeping of such accounts includes the transfer of the individual's balances on the files at the end of a certain period, as for instance at the close of a day's business. The indicators are first set to their normal position, then when any file-holder is used, its indicator 100 must be moved from normal position before files may be inserted in or removed from a file-holder. In all of the forms shown, such movement is necessary and is not in any way dependent on the memory of the operator. 105 At the end of a day's business and assuming that only ten per cent. of the file-holders have been used, the operator may certainly determine at a glance which ones have been used, and a vast amount of time is saved to the person transferring the accounts, because he need only look at the files of those holders 110 which have had their indicators moved from normal to indicating positions.

I claim as my invention:

1. A device for use in keeping accounts comprising a casing, a series of file-holders therein, each adapted to carry loose files, and an indicator for each file-holder normally in a position from which it must be moved in order to withdraw from or deposit a file within its holder, whereby the indicator is certainly changed from normal to indicating position whenever access is had to said file, without having to remember to make such 130

change, and whereby it may be certainly determined, after a certain period, at a glance which file holders have been used during said period.

5 2. A device for use in keeping accounts comprising a casing, a series of file-holders, each adapted to carry files, and indicators for the file-holders, each normally in position from which it must be moved in order to 10 withdraw from or deposit a file within its holder, whereby the movement of the indicator from normal position is not dependent on the memory of the operator, and whereby after a certain period it may be certainly determined at a glance which file-holders have 15 had their indicators moved from normal position during said period.

3. A device for use in keeping accounts comprising a casing, a file-holder therein 20 adapted to carry files, and an indicator mounted on the file-holder normally in a position from which it must be moved in order to have access to its contents, whereby the movement of the indicator from normal posi-

tion is not dependent upon the memory of 25 the operator, and whereby it may be certainly determined at a glance whether or not the indicator has been moved from its normal position to its indicating position.

4. In a device of the class described, the 30 combination of a series of file holders, and an indicator for each file holder, said indicator being normally in a non-indicating position and designed to be set to an indicating position by the operator's act in obtaining access 35 to the file holder.

5. In a device of the class described, the 40 combination of a cabinet, a series of file-holders in the cabinet, and an indicating device for each file-holder, normally in a non-indicating position, and designed to be automatically set to indicating position when access is had to the file-holder.
